UNITED STATES PATENT OFFICE.

REINHOLD PIETSCH, OF UTICA, NEW YORK, ASSIGNOR TO FOSTER BROTHERS MANUFACTURING COMPANY, OF UTICA, NEW YORK, A CORPORATION.

MATTRESS-HOLDER.

1,206,369.

Specification of Letters Patent.

Patented Nov. 28, 1916.

Application filed January 6, 1916. Serial No. 70,556.

To all whom it may concern:

Be it known that I, REINHOLD PIETSCH, of Utica, in the county of Oneida and State of New York, have invented certain new and 5 useful Improvements in Mattress-Holders; and I do hereby declare that the following is a full, clear, and exact description thereof, which will enable others skilled in the art to which it appertains to make and use the 10 same, reference being had to the accompanying drawings, and to the reference-numerals marked thereon, which form part of this specification.

My present invention relates to mattress 15 holders, and particularly to such devices as apply to bed springs composed of coiled springs.

One object of my present invention is to provide a mattress holder of improved construction and efficient operation and one 20 which is readily applied to the standard bed spring composed of coiled springs.

Another object of this invention is to provide a mattress holder which is efficient for 25 the regular work of a mattress holder and yet adapted to be placed in such a position that no part of the holder shall project above the upper level of the bed spring. This is of great advantage when the bed 30 springs are being stored or shipped, in that it economizes space and protects the mattress holder from being damaged or from damaging other things.

A further purpose of my invention is to 35 provide a mattress holder wherein the holder is adapted to be folded or housed within the normal space or level of the bed spring and yet will as soon as released, assume its natural operative position.

Another object of my invention is to utilize 40 the resiliency of the bed spring to hold the mattress holder in erect or operative position and at the same time utilize the compressibility of the bed spring to house the 45 mattress holder in a compact way. Furthermore, my object is to so arrange and combine the parts that the springs will not be strained nor the holder distorted by reason of the holders being housed within the space 50 normally occupied by the bed spring.

A still further object sought to be attained by my invention is to provide a simple mattress holder that can be applied to a great variety of bed springs without change

of construction and which, if desired, may 55 be applied to bed springs already in use.

Another object is to provide a mattress holder that is not only adapted to extend along the sides of the bed spring and fold down thereupon, but also one which extends 60 about the corners of the spring and part way along the ends thereof; and moreover a holder where these end extensions likewise fold down and at all times strengthen the side members of the mattress holder. 65

Further purposes and objects of my invention will appear from the specification and claims herein.

Figure 1 is a plan view of one corner of a coiled-spring bed spring to which has been 70 applied a mattress holder embodying my invention. Fig. 2 is an end view of the same. Fig. 3 is a vertical sectional view on line 3—3 of Fig. 1. Fig. 4 is a vertical sectional view on line 3—3 of Fig. 1, but with the 75 holder depressed.

Referring to the drawings in a more particular description, there is illustrated on a reduced scale one corner of a bed spring composed of the usual coiled springs 6 set 80 on end, mounted in rows and with the upper convolution 7 of adjacent springs secured to each other as by being interlocked as at 8 in the row back from the side of the bed spring or connected by clips 9 as illustrated 85 in the edge row of springs or the row next to the side of the bed spring or by longer clips 10 such as used between adjacent springs of the edge row and the row next thereto. About the upper edge of the bed spring 90 extends the usual edge rod 11, secured to the upper convolution of the spring 6 about the sides and end of the bed spring as by clips 12. The construction of the lower end of the springs 6 or their mounting, not being 95 relevant to this invention, need not be shown or described.

The mattress holding arms in their simplest form have a horizontal portion 13, the inner end of which 14 is secured to the upper convolution of a spring 6 back from the edge of the bed spring, preferably to the outer side of a spring adjacent to an edge spring. From its attached end 14 the horizontal part 13 extends toward the side of 100 the bed spring over the inner side 15 of the upper convolution of an edge spring and then extends across the top of said edge 105 spring.

spring nearly to the outer side 16 of said spring. Before reaching the said outer side of said edge spring the holder 20 turns upward, forming an upstanding portion or finger 17, which engages the outer edge of the mattress and operates to hold the same in place.

Preferably the upstanding fingers 17 will have their upper extremities connected by horizontal means extending longitudinally of the side of the bed spring in order to obviate the presence of sharp upstanding points to give greater holding surface against the mattress so as not to wear the same and so as to more readily enable all of the mattress holding arms to be depressed when necessary.

The preferred form of mattress holding arms 20 is shown in perspective in the drawings. Here the arms are formed in pairs, as it were, in that the two horizontal arms 13 have the upper extremity of their fingers 17 connected by connecting rods 18 rigidly secured to said upstanding fingers. A convenient form of constructing said holders in pairs is to bend the same up out of one piece of material such as a length of wire. A satisfactory construction is to have the two arms 13 of said U-shaped holder spaced apart the distance of from the center of one row of springs to the center of the next row of springs as shown in the drawings by the holders, the arms of which extend to the side of the bed spring. It will be obvious, however, that the horizontal arms 13 of the holders 20 may be spaced a greater distance so as to span two or three rows of springs or might be so close together as to have both of the arms of one holder secured to one and the same spring and project edgeward over the same edge spring. The advantage of having the holders constructed in this U-shaped form is that it provides a simple manner of keeping the upstanding arms 17 in upright position and preventing their being bent sidewise. It will be obvious that the upstanding fingers 17 of one of these double holders being rigidly connected by the connecting rod 18, will readily remain upright without relying upon any particular form of fastening where the ends 14 are connected to the upper convolutions of the springs back from the edge. Furthermore, these U-shaped mattress holders may be used, if desired, without further longitudinal connecting means along the sides of the bed spring, because the rods 18 keep the upper ends of the fingers 17 from doing damage and give a sufficient bearing against the mattress to keep it in place without wear. However, in order to further extend the bearing surface against the mattress and to obviate the presence even of angles along the sides of the mattress and also to make the holders operate more in unison, I prefer to con-

nect the rods 18 along one side of the bed spring with an upper rod 19 secured to the holders at the level of said rods 18 and secured to said rods 18 as by clips 20^a, encircling the short connecting rods 18 and the long upper rod 19.

By reference particularly to Fig. 3 it will be seen that the horizontal arms of the holders 20 where they pass over the inner side 15 of the edge springs are not connected to said edge springs, but simply rest upon the upper surface thereof. The support of the inner sides 15 is sufficient to hold the mattress holders in upward or operative position when the mattress is thereon, because the mattress as plainly indicated in dotted lines in Fig. 3 exerts no downward pressure on the said mattress holder. As already mentioned, the upstanding arms 17 start before the horizontal arms 13 reach the outer side 16 of the edge springs. When it is desired to have the mattress holders in inoperative position or housed, as it were, within the usual space of the bed spring, a downward pressure upon the upwardly projecting parts of the mattress holders will cause them to assume the relative position clearly indicated in Fig. 4. In coming to this position such downward pressure has somewhat compressed the edge spring by reason of the pressure upon its inner side at 15. At the same time the upstanding arms 17 have passed downwardly within the cavities of the respective springs over which they formerly projected. The clearance between the arms 17 and the outer side 16 of the top convolution and the outer side of the convolutions immediately below is sufficient to let the arms 17 pass downwardly within the spring cavities without danger of the holders becoming caught and without danger of damage to the springs. It will be understood, of course, that as soon as the downward pressure upon the mattress holders is released, they will again move up to operative position under the expansive force of the edge springs. When the holders are thus compressed it will be obvious that the short connecting rods 18 and the long top rod 19 will lie along the upper surface of the bed spring.

As a further means of strengthening the mattress holders here described and of preventing dislocation of the parts, especially at the corners of the bed spring, I prefer to have the top rod 19 turned in at the ends of the bed spring and extend some distance along the ends of the bed spring and inclined downwardly and pivotally fastened to the edge rod 5 of the spring bed as at 21, so that movement of rod 19 laterally or longitudinally of the side of the bed is prevented, while at the same time the said rod may freely rise and fall with the pivotal point 21 as the center of said movement.

The construction so far shown may be further strengthened by a one-armed holder 12^a having the upper extremity of its up-standing arm 17^a secured to the part of the 5 rod 19 extending along the end of the bed spring. This holder 12^a may be fastened as at 12^b to the farther side of the spring next to the corner spring, while the horizontal part of said holder extends over the horizontal arm 13 of that spring and under the 10 horizontal arm of the corner spring.

What I claim as new and desire to secure by Letters Patent is:

1. In a mattress holder the combination of 15 a bed spring composed of rows of coiled springs set on end and arms each having one end attached to the top convolution of a spring back from an edge spring and extending over the inner side of said edge spring 20 and having its outer end turned up before the outer side of said outer spring is reached and adapted to engage the outer edge of the mattress and hold it in place, the outer part of said arms with their upturned outer ends 25 being adapted to be forced down into the cavity of the edge springs over which they project.

2. In a mattress holder the combination of 30 a bed spring composed of rows of coiled springs set on end, arms each having one end attached to the top convolution of a spring adjacent to an edge spring and extending over the inner side of said edge spring and having its outer end turned up 35 before the inner side of said edge spring is reached and members connecting the extremities of said upturned ends adapted with said upturned ends to engage the outer edge of the mattress and hold it in place, the outer 40 part of said arms with their upturned ends being adapted to be forced down into the cavity of the edge springs over which they project, and the said connecting members being adapted to then lie flat upon the upper 45 surface of the bed spring.

3. In a mattress holder the combination of 50 a bed spring composed of rows of coiled springs set on end and U-shaped arms having their separate ends attached to the top convolutions of springs adjacent to edge springs and extending over the inner side of said edge springs and having their outer or looped ends turned up before the outer side 55 of said edge springs is reached and adapted to engage the outer edge of the mattress and

hold it in place, the outer part of said arms with their upturned outer ends being adapted to be forced down into the cavity of the edge springs over which they project and the connecting or loop part of said arms being adapted to then lie flat upon the upper 60 surface of the bed spring.

4. In a mattress holder the combination of 65 a bed spring composed of rows of coiled springs set on end, U-shaped arms having their separate ends attached to the top convolutions of springs adjacent to edge springs and extending over the inner side of said edge spring and having their outer or looped ends turned up before the outer 70 side of said edge springs is reached and adapted to engage the outer edge of the mattress and hold it in place, and members connecting the looped upper part of said arm along the edge of the bed spring, the 75 outer part of said arms with their upturned outer ends being adapted to be forced down into the cavity of the edge springs into which they project and the connecting or loop part of said arms, together with the 80 connecting members adapted to lie flat within the upper surface of the bed spring.

5. In a mattress holder the combination of 85 a bed spring composed of rows of coiled springs set on end, arms each having one end attached to the top convolution of a spring adjacent to an edge spring and extending over the inner side of said edge spring and having its outer end turned up before the inner side of said edge spring is reached and 90 members connecting the extremities of said upturned ends adapted with said upturned ends to engage the outer edge of the mattress and hold it in place, the outer part of said arms with their upturned ends being 95 adapted to be forced down into the cavity of the edge springs over which they project and the said connecting members being adapted to then lie flat upon the upper surface of the bed spring, the ends of said connecting members being turned back along the adjacent 100 end of the bed spring and downward to the bed spring edge and hingedly secured thereto.

In witness whereof I have affixed my signature in the presence of two witnesses, this 105 2nd day of November, 1915.

REINHOLD PIETSCH.
